CROSS BRACE FOR LOAD RETAINING DOORS

John W. Leslie, Evanston, Ill., assignor to Signode Steel Strapping Company, Chicago, Ill., a corporation of Delaware

Application August 29, 1955, Serial No. 531,218

6 Claims. (Cl. 160—368)

The present invention relates to cross braces for load retaining doors, which are frequently known as grain doors, and in particular to a novel supporting arrangement for such doors of the nonrigid flexible type as, for example, those shown in the patents to Herbert Corkran No. 2,116,260, dated May 3, 1938, John M. Moon No. 2,310,860, dated February 9, 1943, and John H. Leslie No. 2,595,087, dated April 29, 1952. For convenience in this specification, these load retaining doors may be referred to as grain doors.

Such grain doors are now prefabricated, and comprise a pair of fabric panels combined with a plurality of horizontally disposed reinforcing straps. The panels are usually heavy kraft paper bonded together and enclose therebetween the reinforcing straps, the bonding being by a strong adhesive, such as an asphalt base type.

These grain doors are secured to the doorway frames of the carriers, such as boxcars, by nailing their marginal edges to the posts of the doorway defining frame. It is preferred that the nailing be through the reinforcing straps and many arrangements have been made to insure that this nailing technique is used. It is difficult manually to apply very much tension to the reinforcing straps as the door is nailed in place. While some tension can be applied, usually there is not adequate amount to prevent bulging or sagging of the door outwardly of the car to at least a slight distance. If anchorage of the car doorway post is inadequate or has become loosened, strap tension will sometimes pull the post loose from the car. Bulging is also accentuated when the doorway defining frame is old and the wood is rotten or is badly scarred with the holes left from many previous applications of doorway closing partitions. Under such circumstances the nails do not hold tightly and will give enough so that the nonrigid grain door will flex outwardly.

If the load is heavy granular material, or the nails do not hold properly, the sagging will be pronounced and may be even sufficient so as to prevent or obstruct the normal movement of the main and outer doors of the vehicle which are usually slid across the opening and locked in closed position until the car reaches its destination. In some cases the marginal edges of the grain door will pull from the frame and permit leakage of the granular material.

It is the principal object of the present invention to provide a new and improved cross brace which is separate from the grain door, but which is positioned across the doorway opening and will give added support to the grain door to restrain the door against outward sagging or bulging and to prevent it from pulling loose from the doorway frame.

Another object is to provide a new and improved cross brace for nonrigid grain doors, which permits a shipper safely to use the standard prefabricated doors now commercially available, on old or badly scarred boxcars.

Another object is to provide a new and improved cross

2

brace for nonrigid grain doors, which is self contained and may be reused.

Another object is to provide a new and improved cross brace for nonrigid grain doors, wherein the cross brace is readily put in place and may be hung on a pair of nails from the inner sheathing of the carrier or vehicle.

Another object is to provide a new and improved cross brace for a grain door, which may be easily and quickly removed from the car after it has been unloaded.

10 Another object is to provide a new and improved cross brace for a grain door, which includes a metallic strap against which the outer face of the nonrigid grain door may bear and which will give added support to and prevent undue sagging or bulging of the grain door.

15 Other objects and advantages will become apparent from the following description, taken in conjunction with the accompanying drawings, wherein:

Fig. 1 is a fragmentary perspective view, taken from the inside of a railway freight car or boxcar, showing the 20 cross brace of the present invention applied across the doorway opening and supporting a grain door, with some parts being broken away better to illustrate the invention;

Fig. 2 is a fragmentary elevational view, taken at one end of the horizontal cross brace;

25 Fig. 3 is a plan view of the end of the horizontal cross brace shown in Fig. 2, partially broken into section better to illustrate the construction, and may be considered as being taken along the line 3—3 of Fig. 2;

Fig. 4 is an end elevational view, partially broken into 30 section; and

Fig. 5 is a view similar to Fig. 4, showing a modified form of cross brace.

Referring to the drawings, the reference character 10 indicates in general a load retaining or grain door of the 35 nonrigid type, which may be constructed in accordance with the teaching of any of the previously mentioned patents. This grain door preferably comprises a pair of inner and outer plies of fabriclike material, such as heavy kraft paper, 12 and 14, reinforced with transverse strips of metallic strapping 16. The door is secured to the vertical posts 18 of the doorway frame of a grain or granular material carrying vehicle such as a railway boxcar, by a plurality of nails 20, preferably of the double headed type, which are driven through the reinforcing straps. In this 40 fashion the nonrigid grain door 10 is secured to the doorway frame and closes opening 22 against the leakage of the granular material being transported.

As previously mentioned, under conditions of heavy 50 loading or old and scarred door posts 18, the nonrigid grain door 10 may sag outwardly sufficiently to prevent closing of the main sliding doors of the carrier. In order to restrain the door 10 against such sagging or bulging, the cross brace 24 of the present invention is applied across the doorway 22 in such fashion as to provide added support for the grain door 10.

The cross brace 24 consists essentially of two elements, a generally horizontally arranged hollow column 26 and a flexible metallic strap 28, extending the length of the 60 column and across that face thereof which is directed outwardly of the car and which will be referred to hereinafter as the outer face of the column. Such outer face is indicated in the drawings, for convenience, by the reference character 30.

65 The column 26 preferably includes a hat-shaped section 32 having a generally rectangular hollow main body portion and at its forward edge is bounded by a pair of upwardly and downwardly facing flanges 34 and 36. The open side of the hat-shaped section 32 is closed by an outer face plate 38 which is preferably secured, as by spotwelding, to the flanges 34 and 36, and which provides 70 the outer face 30 of the column 26.

The ends of the column 26 are closed by cover plates 40, each of which at its forward edge is formed with an integral flange 42 overlying the forward face 30 of the face plate 38. The cover plate 40 has welded to its inner face a locating or positioning plate 44 which fits snugly within the hat-shaped section 32, frictionally holds the end plate in position, and adds strength to the column end. To the outer face of the flange 42 is welded a spacer plate 46 which is the same size as the flange 42, and which, with the flange 42, defines an adequate space or slot for the grain door 10 between the strapping 28 and the column face 30. It will be observed from Figs. 1 and 4 that the flange 42 is wider than the outer face of the cover plate 40 and has a length equal to the distance between the upper and lower edges of the hat-shaped section flanges 34 and 36, so that the whole provides a very rigid assembly.

The support strap 28 is positioned across the outer face 30 of the column 26 so that it has a completely free and unattached length between the ends of the column. It is spaced from the outer face 30 by the flanges 42 and spacers 46 to provide the grain door slot. Its opposite ends 47 are bent around and across the ends of the column and the cover plates 40, and are secured to inner face or wall 43 of the column by a plurality of fastening means such as drive rivets 50. At the inner face of the column a spacer and strengthening plate 52 is provided between the strap 28 and the column 26, and which may be omitted if added strength is not desired or if some other fastening means is used in place of the drive rivets, such, for example, as welding. If desired, the strap 28 may be preformed or bent accurately in a fixture to fit across the column face 30, the end plates 40, and the inner face 43, before being secured to the column 26.

As will be observed from Fig. 1, the cross brace 24 is substantially longer than the width of the grain door and is preferably long enough so that it overlies the inner sheathing 54 of the carrier. A cross brace is secured to or hung from the carrier sheathing 54 by a pair of double headed nails 56 which are driven thereinto through apertures 58 extending through the column flange 34, the cover plate flange 42, and the spacer plate 46. It will be observed from Fig. 3 that the strapping 28 lies against the inner face of the sheathing 54 and the doorway defining frame posts 18 and across the outer face of the grain door 10.

The cross brace 24 and grain door 10 are secured across the doorway opening 22 in the following preferred manner: The grain door 10 is held in place so that the fold 11 between the main body of the door and the floor flap 13 just touches the floor of the car. The top of the grain door 10 is then nailed to the posts 18 so that the door will hang and need not be supported by workmen during the installation. The marginal edges of the grain door 10 are nailed to the posts 18 in the normal manner, care being taken to do the nailing evenly at both sides toward the bottom. At a point about one-third of the grain door height, the nailing is halted and the lower portion of the door and the floor flap are threaded through the space between the column 26 and strap 28 of the cross brace 24. The latter is then moved upwardly on the door until the column hits the lowest nails 20, securing the grain door to the posts 18. The nails 56 are then driven into the sheathing 54 to hang the cross brace therefrom. The lower portion and floor flap of the door are nailed into place.

The drawing shows a single cross brace 24 across the doorway opening 22, but it should be understood, of course, that the number and vertical placement of the cross braces is determined by the character and force of the load and the physical condition of the vehicle.

The cross brace 24 gives added support to the non-rigid grain door 10 at the place where the load might cause it to bulge or sag outwardly unduly, and might prevent the ready closure of the main doors of the ve-

hicle. While the grain doors 10 are intended to be used only once, and are usually destroyed in unloading the car, it is obvious that the cross brace 24 has a substantially long life, and unless it is misused or damaged it can be reused.

Where the strap 28 restrains the door 10, the fabric or paper of the door will billow out at the top and bottom of the strap 28, but not so far as to permit the door 10 to pull away from the frame posts 18 or to interfere with closing the car's main doors.

In the foregoing description, the element 26 has been described as a column because it acts primarily in compression like a column does under load conditions. The cross brace 24 is a unit not necessarily fastened to the grain door and the compressive and tensile stresses which are placed on it from the load are self contained. As the grain door 10 under the pressure of the load within the vehicle bears against the strap 28, the latter resists the load primarily by longitudinal tensile stresses. Since the ends of the strap 28 are anchored at the ends of the column 26, the stresses in the strap are exactly balanced by stresses, primarily compressive and longitudinal, in the column 26.

In Fig. 5 there is shown a modified column section 62 and a narrower strapping 28'. The section is a closed box shape made of a single sheet of metal bent so that the forward plate 64 thereof is integral with the bottom, top and inner walls. The forward plate 64 extends upwardly beyond top wall 66 and is welded to an upwardly extending flange 68. End closure plate 70 is constructed in the same fashion as the plate 40, and has a flange 72 and spacer 74 corresponding to the flange 42 and spacer 46, and a locating or positioning plate 75 corresponding to the locating plate 44. In order to accommodate the narrower strapping, the end plate 70 is formed with a pair of inwardly projecting ears 76 to prevent the strapping 28' from slipping off the end of the cross brace 24 to which it is secured by the rivets 50, by spot welding or some other convenient and appropriate means. The function and operation of the modified cross brace shown in Fig. 5 is identical with that of the principal embodiment.

It is, of course, possible that the column 26 be made of square or rectangular tubing to which cover plates are secured in the manner disclosed, and which are fitted with flanges, or other arrangement for hanging the cross brace from the sheathing or inner wall of the car. Also, other cross sectional shapes suitable for columns might be used. The end plates 40 or 70 may take the form of half rounds in order to eliminate the relatively sharp bends in the strapping 28 in order properly to secure it to the inner face of the column.

Other arrangements for securing the strapping to the column might be used. For example, the strapping might be riveted, welded, or otherwise secured to the column with spacers inserted between the strapping and column to provide the grain door slot.

While the preferred mounting for the cross brace 24 is hanging it from a pair of nails driven into the sheathing of the boxcar, other mounting arrangements are possible. For example, the cross brace might be supported by the grain door itself by adhesively securing the outer face of the grain door to the inner face of the strap 28. Or the strap 28 might be laminated between the fabric plies 12 and 14 as are the cross straps 16, and in such manner that the ends of the strap 28 are exposed to be secured, as by welding, for example, to the opposite ends of the column 26.

From the foregoing description it is clear that the objectives which are claimed for the present invention are attained by the structure disclosed and set forth in the following claims.

While a preferred and other embodiments of the cross brace constituting this invention have been shown and described, it will be apparent that modifications and vari-

ations thereof may be made without departing from the underlying principles of the invention. It is, therefore, desired by the following claims to include within the scope of the invention all such variations and modifications by which substantially the results of this invention may be obtained through the use of substantially the same or equivalent means.

What is claimed as new and desired to be secured by United States Letters Patent is:

1. A cross brace for a nonrigid load retaining door, the door being adapted to be secured to the doorway frame of a vehicle, comprising in combination, a substantially rigid member adapted to be secured to the vehicle across the doorway opening and at the inner side thereof, said member having a length greater than that of the load retaining door with which it is to be used, and a flexible, tension resisting element secured at its ends to said member and having an unsecured length extending across the outer face of said member, whereby the load retaining door may be placed between said member and the unsecured length of said element and supported by the latter against bulging outwardly under pressure of the load within the vehicle.

2. A cross brace for a nonrigid load retaining door, the door adapted to be secured to the doorway frame of a vehicle, comprising in combination, a column adapted to be secured to the vehicle across the doorway opening and at the inner side thereof, said column having a length greater than that of the load retaining door with which it is to be used, and a metallic strap secured at its ends to said column and having an unsecured length extending across the outer face of said column, whereby the load retaining door may be placed between said column and the unsecured length of said strap and supported by the latter against bulging outwardly under pressure of the load within the vehicle.

3. A cross brace for a nonrigid load retaining door, the door being adapted to be secured to the doorway frame of a vehicle, comprising in combination, a column adapted to be secured to the vehicle across the doorway opening and at the inner side thereof, said column having a length greater than that of the load retaining door with which it is to be used, a metallic strap secured at its ends

to said column and having an unsecured length extending across the outer face of said column, and means slightly spacing said length of strap from said column, whereby the load retaining door may be placed in the space between said column and the unsecured length of said strap and supported by the latter against bulging outwardly under pressure of the load within the vehicle.

4. A cross brace for a nonrigid load retaining door, the door being adapted to be secured to the doorway frame of a vehicle, comprising in combination, a generally horizontally disposed metallic strap extending across the outer face of the load retaining door, and column means separate from the load retaining door bridging across the doorway opening at the inner face of the load retaining door and to which said strap is secured for holding said strap in door supporting position to restrain the door against bulging outwardly under pressure of the load within the vehicle.

5. A cross brace for a nonrigid load retaining door, the door being adapted to be secured to the doorway frame of a vehicle, comprising in combination, a metallic strap extending across the outer face of the load retaining door, and structural means separate from the load retaining door bridging across the doorway opening and to which the opposite ends of said strap are secured for holding said strap in door supporting position to restrain the door against bulging outwardly under pressure of the load within the vehicle.

6. A cross brace for a nonrigid load retaining door, the door being adapted to be secured to the doorway frame of a vehicle, comprising in combination, a metallic strap extending across the door and in supporting relation thereto to restrain the door against bulging outwardly under pressure of the load within the vehicle, and a column means secured to the opposite ends of the strap and bridging across the doorway opening of the vehicle at the inner side thereof, and said cross brace being supported by the load retaining door.
